US00D663833S

(12) **United States Design Patent**
Ahn et al.

(10) **Patent No.:** **US D663,833 S**
(45) **Date of Patent:** **** Jul. 17, 2012**

(54) **MIXING SYRINGE**

(75) Inventors: **Edward S. Ahn**, Dover, MA (US);
Stephen Capistron, Melrose, MA (US);
Brian Schlossberg, Chestnut Hill, MA
(US)

(73) Assignee: **Pioneer Surgical Technology, Inc.**,
Marquette, MI (US)

(**) Term: **14 Years**

(21) Appl. No.: **29/378,941**

(22) Filed: **Nov. 11, 2010**

(51) **LOC (9) Cl.** **24-02**

(52) **U.S. Cl.** **D24/114**

(58) **Field of Classification Search** D24/112-114,
D24/133, 186, 104, 130, 127; 606/181, 185;

(57) **CLAIM**

We claim the ornamental design for a mixing syringe, as shown and described.

DESCRIPTION

FIG. 1 is a perspective view of the mixing syringe showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a perspective view thereof showing the mixing handle pivoted down for a plunging operation.

The features shown in broken lines depict environmental structure only and form no part of the claimed design.

1 Claim, 5 Drawing Sheets
